William Bennett, of New York, N.Y.
Letters Patent No. 1056. Dated Oct. 12, 1858.

Witnesses:
George N. Buckman.
Mr. Haskell.

William Bennett.

William Bennett, of New York, N.Y.
Letters Patent No. 1056. Dated Oct. 12, 1858.

The schedule is referred to in these Letters Patent, and making, part of the same.

To all, whom it may concern:

Be it known that I, William Bennett of the City, - County, and State of New York, have invented or produced a new and original shape, configuration, or pattern for a cast fire or ash shovel, and I do hereby declare that the following is a full and exact description of the same, reference being had to the accompanying drawings, making part of this specification, in which.

Fig. 1. is a perspective view of the front, and

Fig. 2. a similar view of the back side of the Shovel.

The Shovel is intended to be cast of iron or other material in a single piece. The body of it is rounded at the back end for the purpose of making it non symmetrical in appearance, and the sides and end of it are rounded to meet the bottom so that the ashes, cinders or Coals taken up on it shall leave it with facility. The handle is curved in the direction of its length and also in its cross section, as is fully shown in the drawings.

What I claim as my invention or production, & desire to secure by letters Patent, is the shape, configuration, or pattern for a Cast Fire or ash Shovel herein described and set forth.

Witnessed,

George N. Buckman.

Mo. Haskell.

William Bennett.
